UNITED STATES PATENT OFFICE.

CHRISTIAN WILLIAM MEINECKE, OF JERSEY CITY, NEW JERSEY.

DESIGN FOR A CUP.

SPECIFICATION forming part of Design No. 31,178, dated July 11, 1899.

Application filed June 14, 1899, Serial No. 720,565. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Cup or Vessel, of which the following is a specification.

The feature of this design consists in a vessel or drinking-cup having a body with curved sides and flaring inclined elliptical mouth joining at one end by a concave curve direct to the body and having at the opposite end a concave curve which connects with the curve 15 of the body by a reverse or convex curve, giving the appearance of a pocket, as set forth in the following specification and claim and illustrated in the annexed drawings, in which—

20 Figure 1 is a perspective view of the cup. Fig. 2 is a front elevation of Fig. 1. Fig. 3 is a plan view of the cup.

The body is shown of elliptical or oval form in cross-section and with the sides 1 curved.

The mouth 2 is shown inclined or at an angle. 25 The mouth is flaring and elliptical in shape. At one end of the mouth is a concave curve 3, leading from the mouth edge direct to the curve 1 of the body. At the opposite end of the mouth is a concave curve 4, connecting 30 with the body curve 1 by a convex or reverse curve 5. This curve 5 gives somewhat the appearance of a pocket. The bottom is shown at 6.

The design presents a novel, striking, and 35 characteristic appearance.

What I claim as new, and desire to secure by Letters Patent, is—

The design for a cup substantially as shown and described. 40

In testimony whereof I have hereunto set my hand in the presence of two subscribing witnesses.

CHRISTIAN WILLIAM MEINECKE.
